UNITED STATES PATENT OFFICE

GRAHAM C. WOODRUFF, OF BRONXVILLE, NEW YORK, ASSIGNOR TO THE L. C. L. CORPORATION, A CORPORATION OF DELAWARE

DROP SIDE CONTAINER CAR

Application filed December 18, 1930. Serial No. 503,299.

This invention relates to improvements in container cars of the type broadly disclosed in Reissue Patent No. 16,073, of May 19, 1925, and more particularly to improvements in drop side container cars of the type shown, for example, in my prior application Serial No. 354,637, filed April 12, 1929, Pat. No. 1,788,075; Jan. 6, 1931, and my prior application Serial No. 359,392, filed April 30, 1929, 10 Pat. No. 1,807,268, May 26, 1931, in which the container holding spaces or compartments of a gondola car are formed by transverse bulk heads or partitions, closed at the sides of the car by drop doors designed to be 15 let down to serve as gang planks for the transfer of the containers to and from the car and forming the "drop sides" of the car. This "drop side" type of car is of advantage in allowing the containers to be loaded on or 20 removed from the car without the use of an overhead crane with which many stations are not equipped.

The main object of the present invention is to provide a drop side container car in which 25 the construction of the combined compartment forming partitions and door jambs is simplified and rendered less heavy and cumbersome and more open than in the drop side container cars hereinbefore in use, without 30 sacrifice of strength and durability, and with the advantage of reducing the cost of construction and the amount of dead weight carried by the car, and of producing a car which may be readily and conveniently 35 cleaned and repaired and kept in thorough working condition at materially less cost.

A further object of the invention is to provide a construction which permits ready renewal of abutment parts of the compartment 40 forming partitions when damaged or worn, and which provides a more reliable and efficient type of locking means for preventing casual release of the locking devices holding the drop doors in closed position.

The invention consists of the features of construction, combination and arrangement 45 of parts, hereinafter fully described and claimed, reference being had to the accompanying drawings, in which:

Fig. 1 is a side elevation of a drop side con-

tainer car embodying my invention, with containers mounted therein, and showing some of the drop doors in let down position.

Fig. 2 is a similar view with containers removed and all the drop sides let down. 55

Fig. 3 is a perspective view of the container car, looking toward the car from a point adjacent one end thereof, and showing clearly the construction of the compartment forming partitions and door jambs and the open type 60 of cars produced thereby, some of the drop doors being shown in closed position and others in open position.

Fig. 4 is a vertical transverse section 65 through the car and taken on a line through one of the partitions.

Fig. 5 is a similar sectional view, taken on a line at one side of the partition.

Fig. 6 is a section on line 6—6 of Fig. 5.

Figs. 7 and 8 are sections on lines 7—7 and 70 8—8 of Fig. 4 looking, respectively, toward the cross rail of the partition and toward the floor of the car.

Fig. 9 is a view similar to Fig. 5 showing 75 in dotted lines the door in released position and in dot and dash lines the door in let down position and employed in conjunction with a runway.

Fig. 10 is a view on an enlarged scale of 80 a portion of the car looking toward a closed door.

Fig. 11 is a vertical section on the line 11—11 of Fig. 10.

Referring now more particularly to the drawings, 1 designates a car, of suitable construction other than hereinafter indicated, having a floor or platform 2 and divided by transversely disposed partitions 3 into spaces or compartments 4 to receive the containers 5. The containers 5 may be of the well known 90 forms and constructions in general use, those shown in the present instance being of that type provided with depending feet 6 to rest upon the floor or platform 2. Suitable means may be provided in each compartment for 95 engaging and holding the container from shifting therein. In the present instance, the floor or platform is provided at the corners of each compartment with recesses or sockets 7 to receive the lower ends of the feet 6, or re- 100

taining members thereon, whereby the containers are held from shifting movements.

Each partition 3 comprises a cross bar or rail 8, preferably of metal and of T-shape in cross-section, said bar being horizontally disposed with its flat face uppermost and provided with a depending central flange 9. The ends of the flange 9 of the bar or rail 8 are secured by bolts or rivets 10 to legs, 10 stanchions or upright bracket plates 11 at the sides of the car. These bracket plates rest at their lower ends upon the floor of the car and may be secured thereto by suitable brackets or bracing members, if desired. The leg or 15 stanchion 11 at each side of the car projects outwardly beyond the plane of the adjacent side frame 11' of the car and is disposed between and riveted or otherwise fastened to the upper ends of the transversely extending 20 portions 12 of opposed L-shaped angle metal plates, the lower ends of the said parts 12 of which plates are riveted or otherwise firmly fastened to a filler plate 12', whereby such lower ends of the parts 12 are stayed and held in properly spaced relation. The longitudinally extending parts 13 of the angle metal plates are arranged to form door jambs at the sides of the respective compartments 4, and the lower ends of said parts 13 are 25 riveted, bolted or otherwise rigidly fastened to the side frame 11'. The parts 11, 11' 12 and 13 form posts or standards at the sides of the car, and jambs or abutments against which the door 4 may close, and said parts 30 cooperate with the cross bars 8 to provide arched partitions across the car and subdividing the same into the compartments 4. The cross bars or rails 8 have secured thereto abutment or wear strips 15 of wood or other 35 suitable material, designed, without material addition of weight, to form renewable abutment surfaces increasing the width and strength of the partition bars and forming abutments against which the containers may 40 bear and which will sustain any rubbing wear and relieve the metal bars themselves therefrom, said strips also providing comparatively soft wear surfaces to avoid marring or injuring the containers. These strips fit beneath the body portions of the bars and bear 45 against the flanges 9 thereof and are secured to the flanges by bolts, rivets or other approved fastenings.

The construction of the partitions comprising the cross bars or rails 8, legs 11, angle metal plates 12, fillers 12' and wear strips 15 as set forth, provides very light but strong and durable, partitions for sub-dividing the car into containing receiving compartments 50 which are in communication with each other beneath the cross bars, thus doing away with the use of solid or substantially solid bulk heads of the character heretofore in use. By this means a more open type of car is produced, that is, a car which is open from end

to end beneath the partition bars or rails 8, whereby the use and transportation of a large amount of dead weight, such as exists in solid bulk heads, is avoided, without materially reducing the strength and rigidity of the car 70 and the partitions between the container receiving compartments. This open type of car is not only cheaper to construct, but cheaper to clean and repair in order to maintain it in first class working condition, as 75 access may be more readily and conveniently obtained to all parts thereof. The cross bars or rails 8, in some cases, may be left entirely "in the clear" between the posts to which it is attached, but it is preferable to provide suitable intermediate bracing means, such as inverted U-shaped braces 16 comprising members riveted at their upper ends to the flange 9 and at their lower ends to suitable portions 80 of the car underframe. 85

The car is provided with end walls 17, preferably of stationary or rigid type, and formed of metal plates provided at their upper edges with end cross bars or rails 18, which may include wear strips similar to the 90 wear strips 15. The side walls of the car, however, are of sectional type, each comprising a plurality of independently movable sections or doors 19 equal in number to the compartments 4 and adapted when in normal 95 position to close the normally open sides of said compartments. Each door is provided adjacent its lower corner portions with trunnions 20, fitted to rotate and to have vertical sliding movements in elongated trunnion bearings 21 secured to the outwardly extending flanges or webs 13 of the posts 12. Near their upper corners the posts are provided with bolts or latch members 22 adapted for engagement with elongated bearing 100 and keeper slots 23 in keeper plates 24, also secured to said flanges 13 of the posts 12. The slots 23 open at their upper ends through the forward edges of the keeper plates, whereby each door through the sliding engagement of its trunnions 20 with the trunnion bearings 21 may be swung inwardly and slid downwardly to a closed position in which bolts 22 will rest at the bottom of the keeper slots 23 and hold the door in such position, as shown in full lines in Fig. 9, or the door may be slid upwardly to released position, as shown in dotted lines in Fig. 9, and then downwardly to let-down or open position, as shown in dot and dash lines in Fig. 10. When the door is disposed in open position, it is adapted to function as a gangplank between the car and a station platform, as shown in Fig. 9, allowing a hand truck or other transfer device carrying a container to be moved to and from the station platform for loading the containers into the car compartments 4 or removing the same therefrom.

The bolts 22 and keepers 24 are provided for locking the doors in closed position 130

against outward movement as each door is moved inwardly and downwardly to such position. In addition, there may be provided manually operable latch bolts 25 to engage keepers 26, secured to the flanges 13 of the post 12, for securing the doors in position against any possibility of casual upward displacement. It will be observed, however, that as each door when closed is locked automatically against opening movement by means which, under all ordinary conditions, will hold it securely against opening movement while the car is en route, or at a station, even though the manually operable latches are not latched, there is little or no danger of a door swinging outwardly when the car is in transit and sideswiping another car on an adjacent track. Reinforcements 27 are provided on each door for sustaining the door against bulging and against distorting pressures when employed as a gangplank, and a stop 28 is provided on the side frame 11 for cooperation with each door to further assist in sustaining it against bulging pressures. This stop, when the door is in closed position, engages a recess in a flange at the lower end of the door, and on the door is an abutment strip 29 which reinforces the recessed part of the flange. Handholds 30 may also be provided on the door to further enable it to be readily and conveniently manipulated in its opening and closing movements.

In each door are formed openings 31 with which hooks 32 on a runway board 33 may be engaged to hold the runway board securely against the upper edge of the door when the latter is in position to form a gangway, as shown in Fig. 9.

It is desirable in practice to provide fastening means of automatic type to engage the closed doors and hold the same positively from upward movement, so that, even in the event of failure to engage the latches 25 with their keepers 26, the doors will be held against any possibility of upward movement. The fastening means for this purpose comprises a pivoted gravity or spring-operated locking member 34 for engagement with a locking projection at the upper end of each keeper plate 24, said locking member 34 being pivoted at its inner end to a bar 8, as at 35, and provided at its outer free end with a beveled surface and a hook to engage the locking projection, whereby when the door is closed latch member 34 will automatically move into engagement with the projection. Arranged on each bar 8 for coaction with each locking member 34 is a holding dog 36, pivoted at its inner end, as at 37, and having an outer end 38 forming a stop shoulder for engagement with the pivoted end of the member 34 when said member 34 is in locking position, thus preventing said member 34 from swinging upwardly to released position. Both the locking or latch member 34 and the dog 36

are of sufficient weight to lie in their engaging positions by gravity against any movements of the car liable to shift them to an inoperative position under movements of the car in travel, so that a reliable safety automatic lock will be provided. The locking members 34 or their equivalent are designed to be used at all times whether or not the locking elements 22 and 23 are used. It will be evident, of course, that the secured doors, therefore, can not be opened until the safety dogs 36 are shifted to retracted position.

From the foregoing, it will be seen that my invention provides a container car which enables the objects of the invention to be carried out in a simple, reliable and effective manner, and which will be of requisite strength and durability, while cheaper in construction, than prior cars of this type having solid bulk heads, and that the construction is also such as to adapt the car to be cleaned and repaired in a readier and easier manner, and so that the cost of repairing and maintaining the same in serviceable condition will be reduced. Other advantages of the invention will be readily understood by those versed in the art without a further and extended description.

While the construction disclosed is preferred, it is to be understood that changes in the form, construction, arrangement and proportions of parts may be made within the scope of the appended claims, without departing from the spirit or sacrificing any of the advantages of this invention.

Having thus fully described my invention, I claim:

1. A container car provided with container receiving compartments formed by transverse partitions of openwork character and establishing communication between the respective compartments, each comprising uprights at the sides of the car and a cross bar connecting said uprights, the uprights of adjacent partitions forming doorways for the intervening compartment at opposite sides of the car.

2. A container car having end walls, and a longitudinal series of compartments formed by transverse partitions of openwork construction and establishing communication between the compartments, and closures for the sides of the compartments forming drop side walls of the car.

3. A container car having a longitudinal series of compartments formed by arched transversely extending partitions, said compartments being open at the sides of the car and having jambs formed by the partitions, and doors for said compartments adapted to close against said jambs and providing drop sides for the compartments adapted to serve as gangplanks.

4. A container car having a longitudinal series of compartments formed by arched

- openwork partitions, the compartments being open at the sides of the car and the ends of the partition forming jambs at opposite sides of the openings, and side walls for the car comprising independent sections forming doors for the compartments adapted to close against said jambs.
5. A container car having end walls, compartment forming partitions between the end walls, each partition comprising uprights at the sides of the car and a cross-bar connecting said uprights, said uprights serving as door jambs and doors at the sides of the car for closing the compartments and adapted to close against said jambs and forming the drop side walls of the car.
10. 6. A container car having compartment forming partitions, and renewable wear strips carried by said partitions.
15. 7. A container car having a plurality of container receiving compartments formed by partitions, each partition comprising uprights at the sides of the car and a cross-piece connecting said uprights, and renewable strips secured to the sides of the cross-piece.
20. 8. A container car having a longitudinal series of compartments formed by transverse partitions, each including uprights and a cross-bar, said cross-bar being T-shaped in cross-section, and removable wear strips underlying the horizontal webs of the bar and secured to the flange thereof.
25. 9. A container car having a longitudinal series of compartments formed by transverse partitions, each comprising door jamb forming uprights at the sides of the car and a cross rail connecting said uprights, wear strips secured to the cross rail, and wall forming drop doors at the opposite sides of the car adapted to rest against said jambs to close said compartments.
30. 10. A container car having a floor and a longitudinal series of compartments formed of arched openwork partitions, each embodying flanged members forming uprights at the sides of the car, and a flanged cross-bar connecting said uprights, the flanges of the upright forming members providing door jambs at the sides of the car, and doors adapted to close against said jambs.
35. 11. A container car having a longitudinal series of compartments formed by transverse partitions, each comprising jamb forming uprights at the sides of the car and a cross-piece connecting said uprights, elongated bearings on the uprights, open recessed keepers on the uprights, doors having trunnions and locking projections respectively engaging the bearings and keepers, and means adapted to interlock with the doors to hold the same from sliding movement.
40. 12. A container car having a longitudinal series of compartments formed by transverse partitions, each comprising jamb forming uprights at the sides of the car and a cross-piece connecting said uprights, elongated bearings on the uprights, open recessed keepers on the uprights, doors having trunnions and locking projections respectively engaging the bearings and keepers, and means adapted to interlock with the doors to hold the same from sliding movement.
45. 13. A container car having stationary end walls, a series of partitions between the end walls, each comprising uprights at the sides of the car, and a cross-piece connecting said uprights, said uprights and cross-piece being T-shaped in cross-section, wear strips secured to the cross-pieces of the bars, and independent doors adapted to rest in closed position against the uprights and partitions and to close the sides of the compartments and adapted to drop down to open position to afford access to the sides of the compartments.
50. 14. A container car having end walls and arched partitions forming communicating compartments between the end walls, the portions of the partitions at the sides of the car providing door jambs, and drop doors adapted to close against said jambs.
55. In testimony whereof I affix my signature.
- GRAHAM C. WOODRUFF.
